PRESS OPERATING MOTOR AND CONTROL
MECHANISMClifton S. Malott, Jr., Norwood, Ohio, assignor to
The American Laundry Machinery Company,
Norwood, Ohio, a corporation of Ohio

Application December 24, 1935, Serial No. 55,993

1 Claim. (Cl. 38—31)

This invention relates to a pressing machine of the type used in garment and laundry work, and more particularly to an improved operating motor and control mechanism therefor.

An object of my invention is the provision of a novel operating motor for a press of the type in which a pair of coacting pressing members are relatively movable laterally into and out of registration and, when in registration, relatively movable into and out of pressure engagement.

One of the novel features of my invention is the provision of a pair of operating motors for a press of the type above described, each of the motors being fluid actuated and the operating fluid for the pressure engagement producing motor being supplied through the lateral motion producing motor automatically after the latter motor has caused movement of the pressing members into registration.

Other features of my invention include the novel structural arrangement of press operating motors for accomplishing the above described objects and suitable control mechanism therefor as will more clearly appear from the accompanying drawing and specification.

In the drawing, Fig. 1 is an end elevation of a pressing machine embodying my invention showing the pressing members in full lines in open position and one of the members in broken lines in registration with the other member for a pressing operation, certain of the parts being shown in section to more clearly illustrate the structure; Fig. 2 is a view similar to Fig. 1 showing the press in fully closed position; Figs. 3 and 4 are front elevations of a portion of the control mechanism, Fig. 3 corresponding to the position of the parts in Fig. 1 and Fig. 4 corresponding to the position of the parts in Fig. 2; while Fig. 5 is a section taken on the line 5—5 of Fig. 1.

I have chosen to illustrate my invention as applied to a pressing machine in which the pressing head is mounted in a stationary manner on the frame and a coacting pressing bed is arranged for lateral movement into and out of registration with the head and when in registration arranged for vertical movement into and out of pressure engagement with the head. It will be understood, however, that my invention may be utilized in machines varying from the embodiment shown here and I desire to be limited therein only as defined in the scope of the appended claims.

In the machine illustrated, on a frame 10 is mounted a pressing head 11 which may be heat-

ed if desired in any suitable manner. A carriage 12 is mounted for lateral movement on the frame 10 preferably by rollers 13 which travel upon suitable guide rails 14 on the frame. Sufficient sets of rollers and guide rails are provided, preferably two. A pressing bed 15 is mounted on the carriage for vertical movement relative thereto, the mounting shown comprising a downwardly extending stem 16 on the bed which reciprocates in a sleeve 17 mounted on the carriage. During this vertical movement the bed is held in proper position by a pin 18 which is guided in a suitable bore on the carriage structure.

Movement of the pressing bed is provided by a pair of motors, 19 being arranged to provide the lateral movement into registration and 20 providing the vertical movement into pressure engagement. Motor 19 comprises a cylinder 19a having a piston 19b connected by a rod 19c with a bracket 12a which in turn is supported on the carriage 12. Motor 20 comprises a cylinder 20a having reciprocable therein a piston 20b whose piston rod 20c is in position to engage and raise the stem 16 when the pressing bed is in registering position. The carriage 12 is biased in the open position shown in full lines in Fig. 1 by means of a counterweight 21 attached to the forward side of the carriage by a cable 22 which passes over suitable guide pulleys in the frame. Motive fluid is supplied to the forward face of piston 19b to cause movement of the bed into registration. This supply of motive fluid is by way of the combined flow and exhaust conduit 23, valve casing 24 and conduit 25. Valve casing 24 houses a normally closed inlet valve 24a and a normally open outlet valve 24b, both mounted on a stem 24c for operation by an oscillating cam 26. This cam is rigidly mounted on shaft 27 which extends to the front of the machine in a position convenient for the operator and is actuated by a manual 28 which, when the press is opened, occupies the position shown in Fig. 3.

Means is provided to insure that motor 20 is not operated until motor 19 has moved the bed into registering position with the head. In the form shown this comprises a port 29 located in the wall of cylinder 19a in such a position that it is uncovered to the supply of motive fluid only after piston 19b has made a sufficient stroke to cause registering movement of the pressing bed. An open vent 30 is provided at the rear end of cylinder 19a to provide against the building up of any pressure on the rear face of piston 19b. Port 29 communicates by passageway 31 with the

lower face of piston 20b. An exhaust conduit 32 is provided for cylinder 20a, this conduit leading through valve casing 33 to an exhaust outlet 34. Casing 33 houses a normally closed outlet valve 33a having an actuating stem 33b which is adapted to be engaged by an oscillating cam 35 which is also rigidly mounted upon shaft 27. The relative position of cams 35 and 26 on shaft 27 and the form of these cams is such that with the shaft in the position shown in Figs. 1 and 3, cam 26 permits the spring in casing 24 to close valve 24a and open valve 24b. At the same time the high point of cam 35 engages valve stem 33b and holds valve 33a open against the bias of the spring in casing 33.

With the parts in the position just described the operator arranges the lay of the work upon bed 15 and moves manual 28 in a counterclockwise direction as viewed in Figs. 3 and 4, placing this manual in the position of Fig. 4. This places the cams 26 and 35 in the position of Fig. 2 which permits the closing of valve 33a by its spring and by the action of cam 26 closes valve 24b and opens valve 24a. Motive fluid is then supplied through conduits 25 and 23 to the forward end of cylinder 19a causing a rearward stroke of piston 19b and moving the bed into the registering position shown in dotted lines in Fig. 1. When the parts reach this position the bed raising stem 16 is in position over piston rod 20c and at the same time piston 19b moves to the rear of port 29 uncovering the same to the motive fluid in cylinder 19a and this fluid flowing through passageway 31 raises piston 20b and moves the bed into pressure engagement with the head. Upon completion of the pressing operation the manual 28 may be returned by the operator to the position of Fig. 3, thus returning the cams to the position of Fig. 1 with the following results. The valve actuating surface of cam 35 is arranged to open valve 33a slightly before cam 26 permits return movement of the valves in casing 24 to the position of Fig. 1. The purpose of this is to permit an initial exhaust of fluid from cylinder 20a through conduit 32 and exhaust port 34 to insure a downward movement of the pressing bed under the influence of gravity before any lateral movement of the bed takes place. This prevents disarrangement of the work on the pressing bed. Shortly after valve 33a is opened, cam 26 permits the return of the valves in casing 24 to the position of Fig. 1 which closes the inlet valve 24a and opens the outlet valve 24b. Cylinder 20a is now exhausted through conduit 32 and also momentarily at least through cylinder 19a and conduit 23. Due to the influence of counterweight 21 the bed moves out of registration on its carriage and piston 19b moves toward the forward end of cylinder 19a exhausting fluid through conduit 23 and open valve 24b.

A guard 36 is pivotally mounted at 37 on a portion of the frame and extends lengthwise along the forward edge of the pressing head in a

position to be engaged by the hands of an operator if they are lying upon the pressing bed as it moves into registration. This guard has an operative connection with a mechanism which will return shaft 27 and the cams thereon to a press-opening-producing position if the guard is struck by an operator as the bed is moving toward registering position. This arrangement comprises a servo-motor 38 mounted on the frame and having a piston 38a whose connected rod 38b is adapted to engage a lug 28a rigidly connected with shaft 27 so that a stroke of piston 38a causes clockwise rotation of shaft 27 when the parts are in the position of Fig. 4. The piston 38a is biased into its unactuated position by a spring 38c. Motive fluid is supplied to servo-motor 38 by way of conduit 39 and valve casing 40. This casing houses a normally closed inlet valve 40a having a stem 40b which is adapted to be engaged and operated by a rod 41 which has a suitable connection with the guard 36 so that rearward movement of guard 36 opens valve 40a. In such a case fluid is supplied from conduit 25 through conduit 39 to servo-motor 38 and will move manual 28 and shaft 27 from the position shown in Fig. 4 to that shown in Fig. 3. This action would take place to prevent accident to an operator's hand but it will be understood that instead of returning manual 28 to off position by grasping the manual 28 the same result may be accomplished by pushing upon the guard 36.

The movement of the carriage 12 and the parts mounted thereon is snubbed at both ends of the carriage travel by a double-acting snubber 42 which is connected by link 43 and lever 44 with the carriage 12. The lever 44 is pivotally connected with the carriage at its upper end and has a pin and slot connection with the frame at its lower end to take care of the movement of the lever relative to the frame as the carriage moves back and forth.

What I claim is:

In a pressing machine of the class described, a pair of coacting pressing members relatively movable laterally into and out of registration and when in registration relatively movable into and out of pressure engagement, two fluid actuated motors, one for causing each of said relative movements, means for supplying fluid from said lateral-movement-causing motor to said pressure-engagement-causing motor when the former has completed said into-registration movement, control valves and a fluid conduit communicating with said lateral-movement-causing motor for operating the same, an outlet conduit for exhausting said pressure-engagement-causing motor, a normally closed valve in said outlet conduit, and control means adapted sequentially to open said normally closed valve and to actuate said first named control valves in out-of-registration-producing direction.
